ELECTRON TUBE

James Dwyer McGee, London, England, assignor
to Electric & Musical Industries, Ltd., a cor-
poration of Great Britain

Application May 26, 1933, Serial No. 672,974
In Great Britain June 2, 1932

5 Claims. (Cl. 250—27.5)

The present invention relates to cathode ray tubes and more particularly to means for concentrating and defining the electron ray emitted by the cathode.

5 In many of the systems in which cathode ray tubes are at present used it is desirable that the ray itself should be of as high a concentration as possible whilst its cross-sectional area should be as small as possible. These conditions must 10 be fulfilled, for example, if the ray be used for purposes of scanning in a television receiving system in order to produce upon a fluorescent screen a visible spot of high brilliancy and small size.

15 It has already been proposed to concentrate the ray either by means of a magnetic field produced at the centre of current carrying coils through which the ray is passed, or by means of an electrostatic field produced between two apertured plane electrodes placed normally to the mean direction 20 of the ray. It has also been proposed to limit the cross-sectional area of the ray by means of stops of suitable size placed in the path of the beam.

25 It has been found, however, that the focussing effect produced by these arrangements is comparatively inefficient and that in consequence a large electron loss occurs at those stops designed to reduce the cross-sectional area of the beam, such a loss being particularly noticeable if the 30 electron-emitting surface of the cathode is of comparatively large area.

It is an object of the present invention to avoid the above described loss of electrons at limiting stops, by providing improved means for concentrating the ray into a narrow pencil of electrons.

35 According to the present invention a cathode ray tube comprises an apertured control electrode, two or more apertured auxiliary electrodes and an anode arranged in the tube in the order mentioned, wherein one or more of said auxiliary 40 electrodes is in the form of an annulus having a frusto-conical or other dished shape.

45 According to a further feature of the present invention a cathode ray tube comprises an apertured control electrode, two or more apertured auxiliary electrodes and an anode arranged in the tube in the order mentioned, wherein the sizes of the apertures in said apertured electrodes are dependent upon the positions of the electrodes 50 relative to the cathode, being smaller the greater the distance of the electrode from the cathode.

55 A constructional embodiment of the invention will now be described, by way of example, with reference to the accompanying drawing, in which:

Fig. 1 illustrates, diagrammatically, an ar-

rangement of concentrating electrodes within a cathode ray tube according to the present invention;

Fig. 2 illustrates, diagrammatically, and in greater detail, some of the electrodes shown in Fig. 1 and the electrostatic lines of force between them; and

Fig. 3 illustrates, also diagrammatically, an alternative arrangement of concentrating electrodes within a cathode ray tube according to this invention.

Referring now to Fig. 1, a cathode ray tube comprises a sealed glass envelope 1 a portion 2 of which is of cylindrical shape closed at one end and another portion 3 of which is of frusto-conical shape merging into the open end of the cylindrical part. Upon the base of the frusto-conical portion 3 is deposited a fluorescent screen 4. The indirectly heated cathode 5, which for the moment will be assumed to be of small emitting area, is situated near the closed end of the cylindrical portion 2. The anode 6 is deposited in the form of a metallic coating upon the inner surface of the cylindrical portion 2, and may, if desired, extend somewhat into the open end of the frusto-conical portion 3.

The general direction of the ray is thus along the axis of the tube from the cathode 5 to the centre of the screen 4 on the base of the frusto-conical portion 3.

Close to the cathode 5 is placed a control electrode 7 which is in the form of a cylinder having a plane metallic diaphragm which is disposed normally to the mean direction of the ray and which has a central aperture 8 large enough to allow a high percentage of the electrons emitted from the cathode 5 to pass through. At a small distance from the control electrode 7 is placed an auxiliary electrode 9 which is in the form of a metallic frusto-conical annulus with its smaller diameter end 10 pointing toward the cathode 5, and close to the auxiliary electrode is placed a second auxiliary electrode 11 which is in the form of a metallic cylinder having two diaphragms with apertures 12 and 13. Beyond the second auxiliary electrode 11 is disposed the anode 6, which as already stated is in the form of a metallic deposit on the walls of the tube.

The potentials applied to the electrodes, relative to the cathode, increase positively and progressively in the order 9, 11 and 6, that is to say, the potentials of the electrodes, relative to the cathode, are greater the greater the distance of the electrodes from the cathode. With this arrangement the electrons extracted from the cath-

ode experience an accelerating force from the cathode to the anode and on reaching the cylindrical anode the electrons are projected through the cylinder on to the fluorescent screen 4.

The electrostatic lines of force between the cathode and the first and second auxiliary electrodes are illustrated in Fig. 2. It will be seen that in the neighborhood of the cathode the lines 10 of force are directed towards the axis of the tube and that between the control electrode and the anode the lines tend to crowd on the axis. An electron leaving the cathode is thus urged on to the axis of the tube and, once there, has to cross 15 a line of force in order to diverge from the axis; if it succeeds and diverges outwards it again passes through a field urging it back on to the axis. As a result of this efficient concentration of the ray along the axis of the tube, the sizes of 20 the limiting apertures 8, 10, 12, and 13 in the electrodes 7, 9, and 11 can be made dependent upon the positions of the electrodes with respect to the cathode. The apertures can, in fact, be made smaller the greater their distance from the cathode without seriously affecting the total number 25 of electrons reaching the fluorescent screen 4.

If the tube be used for purposes of scanning in a television system, modulation of the intensity of the ray is effected by varying the potential 30 applied to the control electrode 7 relative to the cathode 5. In practice it has been found convenient to earth the cathode and bias the control electrode at about ten volts negative. The potentials applied to the remaining electrodes, 35 which may be derived from a suitable arrangement of high resistances and one source of high potential, are as follows:—

The frusto-conical electrode is maintained at about two to three hundred volts positive, the 40 second auxiliary electrode at one thousand volts positive and the anode at four thousand volts positive.

The concentrating effect is most efficient when the ratio

$$45 \quad \frac{V_c - V_B}{V_D - V_c}$$

is equal to or less than the ratio

$$50 \quad \frac{b}{c}$$

where V_B , V_c and V_D represent the potentials applied to the control, the frusto-conical and the second auxiliary electrodes respectively, relative 55 to the cathode, c represents the shortest distance between the control electrode and the frusto-conical electrode, and b represents the shortest distance between the apex of the frusto-conical electrode and the second auxiliary electrode.

The electrodes are held in position and adjusted to be accurately co-axial by a suitable arrangement of metal and glass struts (not shown) and insulating spacers 14.

If desired the concentrating effect can be intensified by arranging co-axially in the tube two or more frusto-conical electrodes. Such an arrangement, which is illustrated in Fig. 3, is of particular advantage if the source of electrons is of large emitting area compared to the cross-sectional area of the ray desired.

70 As before, there is arranged, close to the cathode 5, a plane control electrode 7 in the form of a metallic plate having a sufficiently large central aperture 8 to accommodate substantially all of the electrons emitted from the large cathode 5. On the other side of the control elec-

trode 7 from the cathode 5 there is arranged a first auxiliary electrode 9 in the form of a frusto-conical annulus with its smaller diameter end nearer the cathode 5. The opening 10 in the smaller end of the frusto-conical or first auxiliary electrode 9 is slightly less than that in the control electrode 7 and the apex angle of the frusto-conical electrode 9 is comparatively large, of the order of 90° for example. A short distance from this frusto-conical or first auxiliary electrode 9 is arranged a second frusto-conical annular electrode 11 also with its smaller diameter end 12 nearer the cathode. The apex angle of this second auxiliary electrode is considerably less than that of the first, whilst the length of the former is preferably much greater than that of the latter, measured in the direction of the axis of the tube. Following the second auxiliary electrode is the usual anode 6 which is constituted, as before, by the internal silvering on 20 the sides of the cylindrical portion of the glass envelope.

As before, the fixed potentials applied to the electrodes increase in sequence from the control electrode 7 to the anode 6, and with this arrangement the electrostatic lines of force tend to converge, as shown, from the large area cathode on to the axis of the tube. Since this concentrating effect extends well into the space enclosed by the anode, electrons emitted from the cathode are urged on to the axis of the tube and thus the apertures in the electrodes can be made of progressively decreasing sizes, the size of the aperture in the control electrode being the greatest.

Any or all of these apertures may be covered with a metallic mesh as shown in Fig. 3 in order to obtain a more perfect distribution of the lines of force.

By suitable modifications of the sizes, dispositions and potentials of the control and auxiliary electrodes the grid-voltage-anode current characteristic of the tube can be modified to a considerable extent and the conditions existing between the cathode, control electrode and first auxiliary electrode are, in fact, very similar to those existing between the electrodes of an indirectly heated thermionic triode valve.

If desired, more than two auxiliary frusto-conical electrodes may be employed in the tube, in which case, preferably, the apex angles of these electrodes decrease, and the potentials applied to them increase, with increasing distance from the cathode.

Instead of the auxiliary electrodes being of frusto-conical shape as described, they may have any other suitable annular dished shape and their cross-sections perpendicular to the direction of the ray may be other than circular, if desired.

Having now described the invention, what I claim and desire to secure by Letters Patent is the following:

1. A cathode ray tube having an electron source, an apertured control electrode, at least two auxiliary electrodes each having an aperture therein and being in the form of an annulus having a frusto-conical shape and having its narrower end nearer the cathode of the tube and an anode electrode positioned in the tube in the order mentioned, and a screen positioned to receive the developed electrons passed through the aforesaid electrodes to produce luminous effects.

2. A cathode ray tube having an electron source, an apertured control electrode, an auxiliary electrode having an aperture therein and being in the form of an annulus having a frusto-

- conical shape and having the narrower end nearer the cathode of the tube and a second frusto-conical auxiliary electrode in the form of an apertured plane surface and an anode electrode positioned in the order mentioned, said electrodes being adapted to have applied thereto potentials of values V_B , V_C and V_D , said potentials thus applied to the control, frusto-conical and second auxiliary electrodes, respectively, so as to satisfy 5
- 10 the condition given by the expression

$$\frac{V_C - V_B}{V_D - V_C} \leq \frac{b}{c}$$

where b represents the shortest distance between 15 the control and frusto-conical electrode and c represents the shortest distance between the frusto-conical and second auxiliary electrode.

3. A cathode ray tube having an electron source, an apertured control electrode, at least 20 two apertured auxiliary electrodes and an anode electrode positioned within the tube in the order mentioned, each of said apertured electrodes having an aperture of a size which is made progressively smaller in accordance with increasing 25 distance of the electrode from the cathode.

4. A cathode ray tube comprising an electron source, a control grid member arranged substantially adjacent the electron source, a frusto-conical auxiliary electrode member positioned 30 with its apex toward the electron source so that upon applying voltages between the source and the conical member a convergent electrostatic

field serving to force the electrons issuing from the source into the frusto-conical member is produced, and a frusto-conical anode electrode adapted when voltages are applied thereto to produce jointly with the frusto-conical electrode 5 a second convergent electrostatic field to focus the issuing electrons to a sharply defined path, and a screen structure adapted to receive the electron stream produced.

5. A cathode ray tube comprising an electron 10 source, an apertured control electrode positioned adjacent the source, a wire mesh covering supported by the control electrode for causing a more even distribution of the lines of force between the electrodes, a first frusto-conical electrode 15 member and a second frusto-conical electrode member, said frusto-conical electrode members having lengths progressively varying in accordance with the distance thereof from the electron source the electrode most distant being of longer 20 length, and an anode electrode arranged within the tube whereby upon the application of voltages progressively increasing upon all of the electrodes convergent electrostatic fields are produced between the control grid and the frusto-conical 25 members to cause the electron beam to narrow and whereby between the anode and the frusto-conical members a second convergent electrostatic field is produced to cause the issuing electrons to assume a narrow path and to focus on 30 a predetermined surface as a sharply defined spot.
